MUSIC LEAF TURNER

Roberto Dominguez Agurcia, Comayaguela, D. C.,
Honduras

Application December 27, 1941, Serial No. 424,641

6 Claims. (Cl. 84—487)

My invention relates to improvements in music leaf turners for turning either the leaves of sheet music or bound volumes.

The principal object of the invention is to provide a simply constructed, practical apparatus for automatically turning the leaves of music under control of the foot, so that a musician's hands are left free for use in playing a musical instrument and interruption in playing is obviated.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in side elevation of a preferred embodiment of my improved music leaf turner.

Figure 2 is a view in horizontal section taken on the line 2—2 of Figure 1.

Figure 3 is a fragmentary view in vertical section taken on the line 3—3 of Figure 1 and drawn to an enlarged scale.

Figure 4 is a view in top plan, and drawn to an enlarged scale,

Figure 5 is a detail view in front elevation drawn to an enlarged scale,

Figure 6 is a view in vertical section taken on the line 6—6 of Figure 5.

Figure 7 is a detail view in vertical section taken on the line 7—7 of Figure 5, and drawn to an enlarged scale, with reference to the scale of said Figure 5.

Figure 8 is a similar view taken on the line 8—8 of Figure 5.

Figure 9 is a view in horizontal section taken on the line 9—9 of Figure 5.

Figure 10 is a view in plan of one of the hubs for one of the brackets for one of the plate operating bracket arms,

Figure 11 is a view in perspective of one of the tail plates of one of the leaf turning arms,

Figure 12 is a view in vertical section of one of said tail plates and the pivotal connection of the plate carrying bracket arm thereto,

Figure 13 is a view in transverse section taken on the line 13—13 of Figure 10.

Figure 14 is a view in vertical section taken on the line 14—14 of Figure 2 and drawn to an enlarged scale,

Figure 15 is a view in vertical transverse sec-

tion taken on the line 15—15 of Figure 14 and drawn to an enlarged scale,

Figure 16 is a view in side elevation of the contact wheel,

Figure 17 is a view in horizontal section taken on the line 17—17 of Figure 14,

Figure 18 is a view in top plan of a modified embodiment of my improved music leaf turner, adapted for turning the leaves from left to right as well as from right to left,

Figure 19 is a view in bottom plan of the head of the drive shaft of said modified embodiment,

Figure 20 is a view in transverse section taken on the line 20—20 of Figure 19 and drawn to an enlarged scale,

Figure 21 is a view in transverse section taken on the line 21—21 of Figure 18 and drawn to an enlarged scale,

Figure 22 is a view in transverse section taken on the line 22—22 of Figure 18 and drawn to an enlarged scale,

Figure 23 is a view in longitudinal vertical section of a modified embodiment of motor control,

Figure 24 is a view in horizontal section taken on the line 24—24 of Figure 23, and

Figure 25 is a view in longitudinal section of another modified form of motor control.

Referring now to the drawings by numerals, and first to Figures 1 to 17, my improved music leaf turner, in its preferred embodiment, has the form of a music rack including a base casting 1 of tripod form embodying a pair of rearwardly diverging base arms 2 and a forwardly extending elongated motor control box 3 functioning as another base arm, said arms 2 and motor control box 3 radiating from an upright center sleeve 4. Arising from the sleeve 4 is the usual sectional telescopic column including a pair of upper and lower sections 5, 6 relatively adjustable to extend the height of the column. A set screw 7 is provided in the upper section 5 for establishing the desired adjustment of said sections 5, 6. The upper section 5 is provided with a forked upper end 8 through which a transverse pivot pin 9 is extended. Pivotally mounted on the pin 9 for swinging adjustment forwardly and rearwardly is an upstanding bracket plate 10 supporting a motor drive casing 11 having a back wall 12, a flat top plate 13, and a detachable front plate 14 depending below the casing 11 and extending beyond opposite sides thereof to form a back rest for sheets, or a volume, of music, not shown. Extending along the bottom edge of the front plate 14 is a music sup-

porting ledge 15. A pair of hanger bars 16 support the ledge 15 adjacent opposite ends thereof and are vertically slidable in suitable guides 17 fixed to the rear side of the front plate 14. Set screws, as at 18, provided in appropriate guides 17 provide for locking the guide bars 16 in said guides so that the ledge 15 is vertically adjustable into different set positions, as will be clear. A sector 19 is provided on the bracket plate 10 to extend through a slot 20 in the upper section 5 and a thumb screw 21 is extended through said section to be turned against said sector 19, whereby by the bracket plate 10 and motor drive casing 11 may be adjusted swingably forwardly and rearwardly on the pin 9 into different set positions to dispose the music on the ledge 15 at different angles to the vertical. The pin 9 is equipped with a nut 22 to retain the same in place.

The front plate 14 may be fixed to the motor drive casing 11 as represented at 23.

Suitably fixed in the motor drive casing, to the back wall 12 thereof, is a reversible type motor 24 arranged with the armature shaft 25 thereof upright. The motor base 26 may be bolted, as at 27, to the wall 12, if desired. Fast on the upper end of the armature shaft 25 is a gear wheel 28 meshing with an elongated, relatively smaller, gear pinion 29 fast on a drive shaft 30. The drive shaft 30 is rotatably and slidably mounted, in upright position, in the top plate 13 with its upper end extending upwardly beyond said plate for a suitable distance and its lower end slidably mounted in a bearing 31 fixed in a transverse ledge 32 provided in the motor drive casing 11, the arrangement of the lower end of the drive shaft 30 and the bearing 31 being such that said end and bearing cooperate to limit downward sliding movement of said shaft. A spiral spring 33 sleeved onto the drive shaft 30 between the gear pinion 29 and a washer 34 opposed to the plate 13 yieldingly retains the drive shaft 30 in its downward limit of movement.

Above the top of the motor drive casing 13 is a series of leaf turning, rod-like arms 35 normally located on the right hand side of the drive shaft 30, said arms 35 extending lengthwise longitudinally of the top edge of the front wall 14 and being spaced vertically for clearance and also, in their normal position, being spaced laterally rearwardly from each other so that the top arm is normally rearmost and the remaining arms spaced rearwardly successively and equidistantly. The outer ends of the leaf operating arms 35 have suitably secured thereto leaf clamps 36 of the spring pressed clip type, see Figure 8, arranged to hang pendent from said arms 35 and for manual opening to insert the outer upper corners of leaves of music, as at 37, therein and for lightly gripping such leaves to be easily pulled loose therefrom. The inner ends of the leaf turning arms 35 are rigidly secured to one side edge of a series of flat thin tail plates 38, respectively, which in the normal position of said arms, and as best shown in Figures 4 and 6, are arranged one behind the other in engaging relation and in upright position. The opposite side edges of the tail plates 38 are pivotally mounted on the outer ends of a series of plate carrying arms 39 vertically spaced and pivoted as at 39' at their inner ends to a series of stacked disc-like hubs 40 rotatable about the drive shaft 30. For mounting the tail plates 38 on the plate carrying arms 39, the appropriate side edges of said plates are rabbeted, as at 41, to provide a

horizontal shoulder 42 between which and a right angled keeper plate 43 the outer end of the related plate operating arm is inserted, said keeper plate 43 being provided with a vertical pivot 44 extending through the outer end of said arm 39 so that the tail plate is swingable about a vertical axis on said arm. A screw 45 secures the keeper plate 43 to the tail plate 38. The hubs 40 are equipped with the usual type of anti-friction bearings 46.

A suitable upstanding stop lug 47 on the motor drive casing 11 is provided for engaging the rear side of the rearmost tail plate 38 so that said plates may be swung to the right, manually, with the rearmost one engaging said stop and the others disposed forwardly of said rearmost one to thereby establish the normal position of the leaf turning arms 35. As best shown in Figure 7, in the normal position of the leaf turning arms 35 the sheet clamps 36 overlie the right hand end of the ledge 15 for clamping to leaves 37 of music.

On the upper end of the drive shaft 30 and suitably spaced above the stack of hubs 40 is a disc-like concentric head 48 secured on said drive shaft 30 by a hub 49 and a set screw 50. Extending radially from the head 48 is a radial operating arm 51 having a front padded edge 52 and designed to be swung, clockwise as viewed in Figure 4, over the upper edges of the series of tail blocks 38 in slightly spaced relation to said edges. The operating arm 51 is secured in a rabbet 53 in the head 48 by a screw 54.

Pick-up connections are provided in the tail plates 38 for engagement by the operating arm 51 so that said arm under rotation clockwise will pick up the tail plates 38 successively beginning with the foremost one and swing the same from normal position over to an opposite position at the left hand side of the drive shaft 30, together with the leaf turning arms 35 and the plate carrying arms 39. The pick-up connections comprise pins disposed in vertical sockets 53 in the tail plates 38 and similarly spaced between the side edges of said plates. The pin 54 of the tail plate 38 which is located foremost in the normal position of the parts is fixed and extends above the upper edge of said plate into the path of movement of the operating arm 51. The pins 55 of the remaining tail plates 38 are spring pressed, as at 39, to be projected upwardly in limited degree above the upper edge of the other tail plates 38 and are adapted to be retracted into said other tail plates 38, manually, out of the path of movement of the operating arm 51. Each tail plate 38 is provided on the rear side thereof with a stud plate 56 secured thereto by screws 57 and having extending rearwardly therefrom a latching stud 58. The studs 58 on preceding tail plates 38, in the normal position of said tail plates, extend through apertures 59 in succeeding tail plates 38 and into notches 60 in the projectible pins 55 to hold such pins in retracted positions. As will be seen, when each succeeding tail plate 38 is swung away from its preceding tail plate, the locking stud 58 carried thereby is withdrawn from the notch 60 in the pin of the succeeding tail plate to release said pin for projection under the spring pressure exerted thereagainst.

A cam 61 is provided on the under side of the head 48 for engagement with a roller 62 mounted on top of the motor drive casing 11 at the left hand side of the drive shaft 30 by means of a bar 63 and screws 64, the arrangement being such

that when the operating arm is revolved into a suitable position on the left hand side of said drive shaft 30, said cam 61 will engage said roller 62 and the head 48 will thereby be elevated, together with the drive shaft 30, against the tension of the spring 33, such elevation of said head 48 elevating the operating arm 51 above whichever pins 54, 55 it may be engaged with so that said arm releases said pin and the pick-up connection is broken.

A suitable stop 65 is provided on the rear side of the front plate 14 on the left hand side of the drive shaft 30 for engagement by the first tail plate 38 swung over to the left hand side of said drive shaft 30 to establish the limit of turning movement of the foremost leaf turning arm 35. As will be clear, the remaining tail plates 38 will pile up against the foremost one and each other to establish the limits of turning movement of the remaining leaf turning arms 35.

A suitable housing 66 with an open front is provided on top of the motor drive casing 11 to house the head 48, drive shaft 30, and hubs 40.

Reverting now to the motor control box 3 forming part of a preferred motor control, said box 3 is formed of suitable insulation material and is provided adjacent its inner end with an open bottom chamber 57 adapted to be closed at its bottom by a plate 68, also of insulation, forming part of said control box 3 and detachably secured thereto, by screws, as at 69. A foot pedal 70 is pivoted, as at 71, at its front end on top of the housing 3 adjacent the front end of the latter to extend rearwardly above said box and for vertical swinging movement on its pivot 71. The rear end of the pedal 70 rests upon a roller 72 mounted on the upper end of an upright rack bar 73 slidably extended downwardly through the top of the chamber 67 with its lower end slidably mounted in an upstanding sleeve 74 on the plate 68. A coil spring 75 in the sleeve 74 urges the rack bar 73 upwardly into a limit of upward movement thereof as established by a pin 76 on said bar adapted to engage the top of the chamber 67. The rack bar 73 has fixed thereto, as by screws 76, within the chamber 67 a rack plate 77. A horizontal shaft 78 extends across the chamber 67 with its opposite ends mounted by means of anti-friction bearings 79 in opposite sides of the control box 3. Secured on the shaft 78, as at 79', is a contact wheel 80 of insulation having circumferential equidistantly spaced notches 81 therein. An annular commutator plate 82 of conductive metal is suitably embedded in one side of the contact wheel 80 concentrically thereof and provided with outer edge contact fingers 83 bent over the circumference of the wheel 80 intermediate the notches 81 to alternate therewith. A contact roller 84 rides on top of the contact wheel 80 in the vertical center thereof, said roller being carried on one end of a conductor arm 85 having its other end swingably mounted on a horizontal stud 86 extending laterally into the chamber 67 from one side wall of the motor control box 3 and secured to said wall by a nut 87 and washer 88. A leaf spring 89 suitably secured at one end to said stud 86 and overlying the conductor arm 85 yieldingly urges said arm 85 downwardly to engage the contact roller 84 with said contact wheel 80. A gear wheel 90 is mounted on the shaft 78 by means of an anti-friction bearing 91 for free rotation on said shaft alongside the side of the contact wheel 80 opposite to that having the commutator 82 thereon, said gear meshing with the rack 76. A one-way drive 75 from the upper edges of said plates but spaced

ratchet and pawl 92, 93 are provided on the shaft 78 and gear 90, respectively, the arrangement being such that when the rack bar 73 is moved downwardly the contact wheel 80 will be rotated and when said rack bar moves upwardly, the gear 90 will idle relative to said contact wheel 80. A suitable spring pressed roller-type brush 94 is mounted by means of a conductor sleeve 95 in one side of the control box 3 so that the roller 96 rides on the commutator 82. The stud 86 and nut 87 and washer 88 form a binding post for a lead 97 forming one side of a motor circuit, not shown. The brush sleeve 95 is designed to be connected by a lead 98 to the other side of said circuit.

Referring now to the operation of the described embodiment of the invention, depression of the foot pedal 70 through its bearing on the roller 72 moves the rack bar 73 downwardly in opposition to the spring 75 to effect rotation of the contact wheel 80 clockwise, as indicated by the arrow in Figure 14 to revolve one of the contact fingers 83 under and past the roller 84, said roller then seating in a succeeding notch 81 in said contact wheel 80. As the said contact finger 83 passes under the roller 84, the circuit is closed to the motor 24 in a manner which will be manifest to momentarily energize said motor sufficiently to cause the same to spin and rotate the drive shaft 30 clockwise, as viewed in Figure 4, through the medium of the gearing 28, 29.

The leaf turning arms 35, tail plates 38, and plate carrying arms 39 being in the recently described normal position, such operation of the drive shaft 30 rotates the head 48, clockwise, to revolve the operating arm 51 correspondingly. The pins 55 having been manually retracted into latched position in the tail plates 38, with the exception of the pin 54, said operating arm 51 picks up said pin 54 on the foremost tail plate 38 and swings the same from normal position over to the left of the drive shaft 30 against the stop 65 thereby swinging the leaf turning arm of said tail plate to turn the music leaf to which the clamp 36 thereof is attached, the plate carrying arm 39 of said foremost plate 38 being swung around to the left hand side of the drive shaft, as will be clear. Before the foremost tail plate 38 abuts the stop 65, the cam 61 rides over the roller 62 and thereby elevates the head 48 and operating arm 51 to release the pin 54 of the foremost tail plate 38. As soon as the foremost tail plate 38 is swung away from the succeeding tail plate 38, the stud 58 on said foremost plate 38 is withdrawn from the notch 60 of the pin 55 of the succeeding tail plate 38 and said pin released for projection by its spring 39. Upon another operation of the motor 24, the operating arm 51 picks up the projected pin 55 to swing the second from the front tail plate 38 over against the foremost tail plate 38 to turn the next leaf attached to the clamp 36 of the related leaf turning arm 35. The remaining tail plates 38 will be swung over to the left successively under successive operations of the motor 24 to turn successive leaves of music in a manner which will be apparent and requires no further explanation.

Referring now to Figures 18 to 21, and 25, illustrating the modified embodiment of my music leaf turner adapted for turning leaves of music from left to right as well as from right to left, in this embodiment the tail plates 98 of the leaf turning arms 99 are provided with fixed pick-up pins 100 of the same height upstanding from the upper edges of said plates but spaced

different distances from the inner edges of said plates so that in the normal positions of the plates at the right hand side of the drive shaft 101, said pins beginning with that of the foremost plate 98 are spaced successively at a greater distance from the axis of the drive shaft 101. Tail plate carrying arms 102, similar to arms 39, are fixed to the hubs 103, similar to hubs 40, and also fixed to the inner side edges of the tail plates 100. The operating arm 104 is secured, as by screws 105, on top of the head 106 of the drive shaft 101 in radial position.

Endwise slidable in a longitudinal groove 107 in the top of the operating arm 104 is an elongated pick-up slide 108 extending through an end guide 109 on said operating arm, said slide having a depending pick-up rod 110 fixed in its outer end for picking up the pins 100. Threaded longitudinally in said slide 108 and extending out of the rear end thereof is a screw shaft 111 having its rear end journaled in a split bearing 112 provided on top of the operating arm 104. A gear pinion 113 is fixed on said journaled end of the shaft 111 in the split of the bearing 112 whereby said shaft 111 is rotatable by said pinion and prevented from endwise movement. The pick-up slide 108 is normally positioned on the operating arm 104 so that the pick-up rod 110 under clockwise rotation of said arm picks up the pick-up pin 100 of the foremost tail plate 98.

Suitably fixed in the housing 114, corresponding to housing 66, is an arm 115 extending forwardly radially of the drive shaft 100 and including a front end extension barrel 116 secured thereto by screws 117 and forming a bearing for an upright stud 118 slidable therein and forming an axial reduced extension of said drive shaft 101. A nut on the stud 118 turned against the head 106 secures the head on the stud 118. On the under side of the bar 116 is an arcuate toothed rack 119 engaged by the gear pinion 113 when the operating arm 104 is rotated into a rearwardly extending position.

The head 106 is provided with a cam 120 similar to cam 61 for engagement with a roller 121, similar to roller 62, to elevate the head 106 and operating arm 104 so that the pick-up rod 110 will release the pick-up pins 100. The cam 120, in this instance, is dovetailed, as at 122, into a dovetail quadrant edge slot 123 formed in the bottom of the head 106, one side of the slot being formed by an arcuate keeper plate 124 mortised into the bottom of said head 106 and secured thereto by screws 125.

Referring now to Figure 25, in conjunction with the described modified embodiment of the invention, a motor reversing switch is provided in an open bottomed chamber 126 formed in the outer end of a control box 127, similar to control box 3 previously described, the chamber 126 being closed at its bottom by a base plate 128, similar to base plate 68. The reversing switch is designed to be operated by the front, or heel, end of a foot pedal 129, corresponding to foot pedal 70, said heel end being pivoted, as at 130, to the upper end of an upstanding switch operating rod 131 slidably extending downwardly through the top of the chamber 126 with its lower end slidably in a sleeve 132 upstanding from the base plate 128. A coil spring 133 in said sleeve urges the plunger rod 131 upwardly. A flanged collar 134 fast on said rod 131 engages the top of the chamber 126 and limits upward movement of the plunger rod 131. The flanged

collar 134 overlies one end of a switch lever 135 in the chamber 126 pivoted, as at 136, intermediate its ends whereby under downward movement of the plunger rod 131 the other end of said switch lever is swung upwardly in opposition to a suitably connected coil spring 137 and into engagement successively with a pair of vertically spaced fixed contacts 138, 139. The contacts 138, 139 are designed to be arranged in the motor circuit, not shown, in any well known manner so that when the switch lever 135 is engaged with the lowermost contact 138 the circuit is conditioned to operate the motor in a direction, here in terms forwardly, to rotate the head 106 and operating arm 104 clockwise, as viewed in Figure 18, and when the switch lever 135 is engaged with the upper contact 39, the motor is reversed to rotate said head 106 and operating arm 104 counterclockwise, as viewed in Figure 18.

It is to be understood in connection with the described modified embodiment of the music leaf turner that, with the exception of the modifications described, otherwise the construction and arrangement is the same as set forth in the preferred embodiment of the invention.

Describing now the operation of the modified embodiment, with the tail plates 98, leaf turning arms 99, and plate carrying arms 102 in the normal position described with reference to the preferred embodiment, if the heel end of the foot pedal 129 is depressed to move the plunger rod 131 downwardly in opposition to spring 137 to operate the switch lever 135 into engagement with the lower contact 138, and the motor then energized momentarily in the manner already described with reference to the preferred embodiment, the head 106 and operating arm 104 will be rotated clockwise, as viewed in Figure 18, and the pick-up rod 110 will pick up the pick-up pin 100 of the foremost tail plate 98 and swing said plate, and arms 99, 102 over to the left hand side of the drive shaft 101 thereby turning a music leaf from right to left. As the music leaf nears fully turned position, the cam 120 will ride over the roller 121, said cam being slid, in this operation, to one end of the slot 123, and the head 106 and operating arm 104 will be raised to release the pick-up pin 100 of said foremost tail plate 98. As said arm 104 rotates past the rack 109, the gear pinion 113 engages said rack and is thereby rotated, such rotation of said pinion turning the screw shaft 111 to feed the pick-up slide 108 and rod 110 outwardly of said arm 104 into a position such that the rod 110, under a second rotation of said arm 104, will pick up the pick-up pin 100 of the succeeding tail plate 98 to perform a similar leaf turning operation. These operations may be repeated under successive rotations of the operating arm 104 until all desired music leaves are turned, as will be apparent.

Now, if it is desired to turn the music leaves back from left to right, the heel end of the pedal 129 may be further depressed to, in a manner which will be clear, to engage the switch lever 135 with the upper contact 39, and the motor energized in the manner already described, whereupon said motor will operate reversely to rotate the head 106 and the operating arm 104 counterclockwise, as viewed in Figure 18. Under such counterclockwise rotation of said arm 104 the pick-up rod 110 will engage the pick-up pin 100 furthest from the drive shaft 101, which pin will now be on the foremost tail plate 98 and the left

hand side of the drive shaft 101, and said rod 110 will swing said plate with its arms 99, 102 from left to right to correspondingly turn the foremost left hand music leaf, it being understood that in this operation, the operating arm 104 must be started from the left hand side of the rack 109 after the last right to left hand turn has been made. As the turned sheet nears its fully turned position, the cam 120 engages the roller 121 and is slid to the other end of the slot 123 by such engagement, after which it rides over the roller 121 and the pick-up rod 110 is released from the pin 101, just as previously described. Under a second rotation of said operating arm 104, after the releasing operation just described, the gear pinion 113 engages with rack 119 and rotates the screw shaft 111 to retract the pick-up slide 108 into a position such that the pick-up rod 110 will pick up the succeeding or next pin 100 and the next leaf will be turned from right to left. The manner in which the remaining leaves may be turned from right to left will be clear from the foregoing.

Referring now to Figures 23 and 24, a modified embodiment of motor reversing switch is shown 25 therein for use alongside the motor control box 3 either attached thereto or detached therefrom, as desired.

The modified embodiment of motor reversing switch comprises an elongated rectangular casing 150 of insulation material having a pair of vertical end guides 151 in the longitudinal center thereof and a longitudinally extending bar 152 of insulation material having end notches 153 straddling the guides 151 whereby said bar 152 is vertically movable. A central guide stud 154 depends from the bar 152 into a guide sleeve 155 upstanding from the bottom of the casing 150, said stud being backed by a coil spring 156 in the guide sleeve 155 urging said stud 154 and bar 152 upwardly. A wear plate 156 surrounding the stud 154 is provided on the bottom of the bar 152 to prevent the latter from engaging the sleeve 155. A foot operative plunger rod 157 is slidably extended downwardly through a sleeve 158 in 45 the top of the casing 150 with its lower end threaded through a wear plate 159 and into the bar 152, said plate 159 being suitably attached to said bar. The plunger rod 157 is provided with a head 160 for engagement by the heel of an operator. A pair of insulation posts 161 depend from the top of the casing 150 upon opposite sides of the plunger rod 157 which, it should be explained, is located in the center of said casing 150. The lower ends of the posts 161 are 55 capped by a pair of carbon contacts 162'.

A pair of conductor rods 163, 163' extend upwardly from the contacts 162, 162' through the posts 161 to a pair of binding posts 164, 164' on the top of the casing 150. A pair of contacts, such as known at 165, 165', extend through the bar 152 in vertical alignment with the contacts 162, 162', and are normally engaged with the latter under the urge of the spring 166. A pair of conductors 166, 166' extend from the contacts 165, 165', within the bar 152, with ends extending through the top of said bar, said conductors being connected by a pair of leads 167, 167' to a pair of binding posts 168, 168' on the top of the casing 150. A pair of contacts 169, 169' are provided in the bottom of the casing 150 in vertical alignment with the contacts 165, 165' to be engaged with the latter under depression of the bar 152. In the top of the casing 152 is a pair of conductor members 170, 170' at opposite ends 75

of said top, respectively. The line 171 extends from the source of power, not shown, to the binding post 168 and a similar line 172 to the binding post 168'. A line 173 extends from binding post 164 and a line 165 from the binding post 164'. A line 174 extends from the source of power. The switch is designed for use with a three-phase induction type motor and the lines 171, 172, 174 to be connected in the usual manner to the motor field. Contact 170 is connected to contact 169 by a line 175 and said contact 170 is connected to line 165 by a line 176. Contact 170' is connected to contact 169' by a line 177 and contact 170' is also connected to line 173 by a line 178. The previously described motor switch in motor control box 3 is connected with the line 174, as represented at 179.

In the normal position of the reversing switch, the contacts 165, 165' are engaged with the contacts 162, 162' and disengaged from contacts 169, 169'. Switch 179 being closed, the current flows, by way of line 171, post 168, lead 167, conductor 166, contact 165, contact 162, conductor 163, post 164, and line 173 to one side of one phase of the motor field, and to the other side of said phase by way of line 172, post 168', lead 167', conductor 166', contact 165', contact 162', conductor 163', and lead 165. The motor is then conditioned for rotation in one direction. To reverse the motor, the foot plunger 157 is depressed to lower the bar 152 and disengage contacts 165, 165' from contacts 162, 162', and engage the same with contacts 169, 169'. The current now flows to one side of the one phase of the motor field by way of line 171, post 168, lead 167, conductor 166, contact 165, contact 169, line 175, conductor member 170, line 176, and line 165. Current is supplied to the other side of said one phase by way of the line 172, post 168', lead 167', conductor 166', contact 165', contact 169', line 177, conductor member 170', line 178, and line 173. Thus the direction of flow of the current is reversed in one phase of the motor field and the motor caused to operate in a reverse direction.

The foregoing will, it is believed, suffice to impart a clear understanding of my invention without further explanation.

Manifestly, other modifications of the invention than those herein described may be resorted to without departing from the inventive concept, and right is herein reserved to such other modifications as fall within the scope of the subjoined claims.

What I claim is:

1. In a motor operated music leaf turner, a tripod-type base including elongated base members radiating from a common center and one comprising a forwardly extending motor control box, a depressible foot pedal surmounting said box, a column arising from said base in said common center, means at the top of said column for supporting leaves of music to be turned, a casing in the rear of said means, a reversible motor in said casing, leaf turning means on top of said casing operative in opposite directions under forward and reverse operation of said motor to turn said leaves in opposite directions, and a pair of motor energizing and reversing switches, respectively, disposed in said box and operative selectively under depression of said pedal.

2. In a motor operated music leaf turner, means to support leaves of music to be turned

and including a back rest, a motor casing in the rear of said rest, an upright drive shaft in said casing, rotatably mounted and having an upper end extending out of the casing above said rest, a motor in said casing operatively connected to said shaft, a series of leaf turning units above said rest rotatable from normal position about said extending end of the drive shaft to thereby turn said leaves, and means to rotate the units of said series successively under rotation of said drive shaft including an operating arm mounted on said drive shaft for rotation thereby above said series of units.

3. In a motor operated music leaf turner, means to support leaves of music to be turned and including a back rest, a motor casing in the rear of said rest, an upright drive shaft in said casing, rotatably mounted and having an upper end extending out of the casing above said rest, a motor in said casing operatively connected to said shaft, a series of leaf turning units above said rest rotatable from normal position about said extending end of the drive shaft to thereby turn said leaves, means to rotate the units of said series successively under rotation of said drive shaft including an operating arm mounted on said drive shaft for rotation thereby above said series of units, and pick-up connections on units of said series, respectively, for engagement by said arm.

4. In a motor operated music leaf turner, means to support leaves of music to be turned and including a back rest, a motor casing in the rear of said rest, an upright shaft in said casing, rotatably mounted and having an upper end extending out of the casing above said rest, a motor in said casing operatively connected to said shaft, a series of leaf turning units above said rest rotatable from normal position about said extending end of the drive shaft to thereby turn said leaves, means to rotate the units of said series successively under rotation of said drive shaft including an operating arm mounted on said drive shaft for rotation thereby above said series of units, and pick-up connections on units of said series, respectively, for engagement by said arms comprising pins constructed and arranged for projection into the path of rotation of said arm, said pins being spring

pressed for projection and arranged for retraction out of said path, and means on said units for releasably retaining said pin retracted in the normal position of the units and releasing the pins under rotation of the units from normal position.

5. In a motor operated music leaf turner, means to support leaves of music to be turned and including a back rest, a motor casing in the rear of said rest, an upright drive shaft in said casing, rotatably mounted and having an upper end extending out of the casing above said rest, a motor in said casing operatively connected to said shaft, a series of leaf turning units above said rest rotatable from normal position about said extending end of the drive shaft to thereby turn said leaves, means to rotate the units of said series successively under rotation of said drive shaft including an operating arm mounted on said drive shaft for rotation thereby above said series of units, and pick-up connections on said arm and units, respectively, including a member shiftable on said arm into different positions thereon as an incident to repeated rotation of the arm, and pins on said units arranged to intercept said member in the different positions thereof, respectively.

6. In a motor operated music leaf turner, means to support leaves of music to be turned including a back rest, a motor casing in the rear of said rest, an upright drive shaft in said casing rotatably mounted and endwise movable, a motor in said casing operatively connected to said shaft, a series of leaf turning units above said rest rotatable from normal position about said extending end of the shaft, to thereby turn said leaves, means to rotate said units of said series successively under rotation of said drive shaft including an operating arm mounted on said drive shaft for rotation thereby above said series of units, said means including pick-up connections on said units arranged to intercept said arm, said arm being movable under endwise movement of said shaft in one direction to clear said pick-up connections when said units have turned said leaves, and means to move said shaft in said direction under rotation thereof.

50 ROBERTO DOMÍNGUEZ AGURCIA.
